UNITED STATES PATENT OFFICE

140,825

DESIGN FOR A DOLL

James R. Nesbit, Chicago, Ill.

Application December 26, 1944, Serial No. 117,097

Term of patent 3½ years

(Cl. D34—4)

To all whom it may concern:

Be it known that I, James R. Nesbit, a citizen of the United States, residing at Chicago, in the county of Cook and State of Illinois, have invented a new, original, and ornamental Design for a Doll, of which the following is a specification, reference being had to the accompanying drawing, forming part thereof.

The figure is a perspective view of a doll showing my new design.

The doll back and side not shown in the figure are substantially the same as the doll front and side which appear in the drawing.

I claim:

The ornamental design for a doll, as shown and described.

JAMES R. NESBIT.
